MEANS FOR REMOVING FOREIGN BODIES
FROM FEED REGULATORS OF PRESSURE
FED HYDRAULIC SUPPLY CIRCUITS

George Wood, London, England, assignor to Vickers-Armstrongs Limited, London, England, a company of Great Britain

Application June 19, 1947, Serial No. 755,660
In Great Britain November 20, 1946

4 Claims. (Cl. 137—69)

1

This invention relates to means for removing foreign bodies from, or preventing the accumulation of foreign matter in, automatic feed regulators for pressure fed hydraulic supply circuits, such as e. g. in pressure fed water supply circuits of boiler installations.

It is customary in boiler feed installations and other hydraulic fluid supply circuits fed from a feed pump to regulate the discharge to the boiler or other consuming unit by means which responds to the level, or rate of consumption, of liquid in the consuming unit, and the general practice, particularly in boiler feed installations is to provide a float controlled lift valve, the connection from the arm of the float to the valve being by means of a sliding rod passing down through the base of the valve housing into a liquid compartment accommodating a float, the upper end of this rod abutting against the lower end of the lift valve which is provided with suitable guides and a mitre or other suitable enlargement adapted to seat by gravity in a port between the inlet and outlet of the valve housing. It is found that such regulators frequently fail, or do not respond in the desired manner, because of the accumulation of foreign matter in the valve seating, and also, with some forms of valve in the guides for the valve and the rod engaging the lower end of the valve, and the object of the present invention is to provide means for keeping the moving parts of the regulator having fine clearances free from foreign matter by the use of only a filtered small fraction of the feed supply without the need to resort to the less desirable and impracticable method of filtering all of the feed supply.

According to the present invention, means for removing foreign matter from, or preventing the accumulation of foreign matter in, automatic feed regulators for pressure fed hydraulic supply circuits, comprises a by-pass across the pressure supply line to the regulator, the discharge end of this by-pass being positioned so as to direct the water fed there-through into intimate engagement with the moving valve parts of the regulator from which foreign matter is to be cleared, the bore of the discharge of the by-pass being considerably less than that of the normal feed supply line to the regulator, and means in the by-pass to filter the liquid before it reaches the valve housing.

In order that the invention may be clearly understood and readily carried into effect drawings are appended hereto illustrating two embodiments thereof by means of the sectional elevation

2

of Figure 1 showing an embodiment suitable for use in a system in which the feed pump discharges to the feed regulator via a feed heater or heaters, and the outside elevation of Figure 2, showing an arrangement in which a booster pump is introduced owing to the feed pump discharging direct to the feed regulator.

Referring to the drawings which shows the invention applied to a boiler feed installation, the normal or main feed of water to the boiler is from a pump 1 via a conduit 2 connected to the inlet 3 of the regulator shown as a lift type of valve 4 in a valve housing 5. The regulating means for the valve 4 is of the known type in which a float 6 is carried by an arm 6 free to swing about a fulcrum 16 within a boiler water level housing 7 connected to the boiler by an inlet 8, the housing 5 being connected to the boiler by the outlet 9.

The lift valve 4 has, in known manner, a central bore 4' against the lower end of which seats a regulator or auxiliary valve 4a operated by the float arm 6, and the top of the valve 4 is extended to form a piston 17 of larger diameter than the valve 4 and moving in a chamber 18, the space between the base of the piston 17 and the valve 4 being subjected to the pressure prevailing in the boiler. It will be evident that when the float rises to a predetermined level the auxiliary valve 4a will open the lower end of the passage 4' so that water can flow into the chamber 18 above the piston 17 to establish the pressure of the feed pump discharge on top of the piston 17 to hold the valve closed. When the water level in the housing 7 falls sufficiently the float raises the auxiliary valve 4a until it cuts off the flow of water through the passage 4'. Subsequently the water in the chamber 18 bleeds back into the housing 5 through the working clearance between the piston 17 and the bore of the chamber 18.

The foregoing operation is well known, but the present invention is primarily concerned with means to keep the moving parts in the lower structure of the valve 4 having fine clearances free from foreign matter by flooding them with filtered water.

In the latter connection, the lower portion 5a of the regulator housing receives the lower stem part 4b of the valve 4 which is guided in a guide 11 in the lower portion 5a and which is formed with openings 12 connecting the inlet 3 to the interior of the lower part 5a, the purpose of these openings 12 being to enable water fed via filtering means into the lower part 5a from a by-pass

conduit 10 to pass part to the normal main feed supply to the boiler and part to the boiler via clearances around the auxiliary valve 4a.

The by-pass conduit 10 is adapted to discharge into the portion 5a of the regulator containing the guide 11 for the lift valve 4, so that the interior of the valve housing is flooded with water delivered from the by-pass, this water passing with the normal main feed to the boiler via openings 12, and the by-pass conduit 10 containing a form of filter 13 suitable for removing sediment and other foreign matter from the water.

The by-pass conduit is connected at one end to the feed discharge preferably close to the pump 1, and the bore or restriction 14 in the supply line between this connection and the feed regulator compared with the main feed supply line to the boiler is so devised that the pressure of the filtered water supply at the regulator is greater than the main feed water supply at the boiler.

In the embodiment shown in Figure 1 the pressure drop through the conduit 2 into the regulator is assumed to be greater than through the by-pass conduit 10 owing to the conduit 2 containing the usual feed heater or heaters, which are not shown. However, when the feed pump discharges direct to the feed regulator 1, an auxiliary pump 15, as shown in Figure 2, is connected to the main feed discharge line 2, this auxiliary pump being designed to increase the pressure of the water in the auxiliary line sufficiently to overcome the resistance of the filter 13 in such line and to discharge to the regulator at a pressure greater than the main feed discharge at the boiler. This auxiliary pump may be constructed and adapted to function as an additional stage of the main boiler feed pump or may be driven independently by a small electric motor or other available power unit.

Where the present invention is to be adapted to a battery of boilers or other consuming units steaming or otherwise operating at approximately the same pressure, one filtered water supply may be arranged to discharge to each of the several regulators.

I claim:

1. In combination with an automatic feed

regulator of the type incorporating a main valve and an auxiliary valve co-operating therewith, and in which the regulator is connected via a supply line to a feed pump, means for removing foreign matter from, or preventing the accumulation of foreign matter in, the automatic feed regulator, comprising a by-pass across the pressure supply line to the regulator, the discharge end of this by-pass being positioned so as to direct the water fed there-through into intimate engagement with the moving valve parts of the regulator to clear foreign matter therefrom, the bore of the discharge of the by-pass being considerably less than that of the normal feed supply line to the regulator, and means in the by-pass to filter the liquid before it reaches the valve housing.

2. Means for removing foreign matter from, or preventing the accumulation of foreign matter in, automatic feed regulators for pressure fed hydraulic supply circuits, according to claim 1 including boosting means in the by-pass to boost the flow of water received through the by-pass and filtering means.

3. Means for removing foreign matter from, or preventing the accumulation of foreign matter in, automatic feed regulators for pressure fed hydraulic supply circuits, according to claim 2 wherein the boosting means is interposed between the normal feed supply and the filtering means.

4. Means for removing foreign matter from, or preventing the accumulation of foreign matter in, automatic feed regulators for pressure fed hydraulic supply circuits, according to claim 3 wherein the boosting means is an auxiliary pump.

GEORGE WOOD.
